PRESSING DEVICE FOR GARRISON CAP COVERS AND THE LIKE

Paul A. Loomis, Philadelphia, Pa.

Application January 20, 1950, Serial No. 139,752

4 Claims. (Cl. 223—26)

(Granted under the act of March 3, 1883, as amended April 30, 1928; 370 O. G. 757)

1

The invention described herein, if patented, may be manufactured and used by or for the Government for governmental purposes without the payment to me of any royalty thereon.

This invention relates to pressing devices for holding washed garrison cap covers and the like during the ironing operation.

Stretchers for holding military cap covers while drying are disclosed in a number of patents, for example, Nos. 1,703,398 dated February 26, 1929 and No. 2,107,961 dated February 8, 1938. Also it is old to stretch by hand power an old-fashioned beaver or silk hat while subjecting it to steam heat applied on the interior, as disclosed in the McLoughlin Patent No. 388,497 dated August 28, 1888.

However, these prior art constructions do not show a form which is automatically adjustable to different sizes of garrison caps yet provides an upper ironing surface which is unyielding to the pressure of an iron and permits smoothing of the entire top of the cap cover with the aid of internal heat; nor do they show means for imposing stretching tension automatically, that is, without manual power, foot power, or manually operated screws, toggles, wedges, etc. These desiderata are some of the features of the preferred embodiment of the invention illustrated in the accompanying drawings forming a part of this specification.

In said drawings,

Fig. 1 is a sectional elevation, showing in phantom the cap cover applied to the form and showing in dotted lines alternative positions of the movable section of the form;

Fig. 2 is a top plan view of the form per se; and

Fig. 3 is a side elevation.

Referring particularly to the drawings, the form includes a base 10 which may be of die cast metal or other material and has bores 11 by which it may be bolted upon a support 12 such as a table or bench. Secured to the base 10 is a fixed head section which consists of a leg 13 rising from the base, and a hollow head 14 having a polished flat top surface 15 with a curved or arcuate shape as viewed from above (Fig. 2) subtending an angle of at least 210°. The chamber 16 within the head provides a steam space and a pipe 17 coupled to the head and to a source of steam pressure (not shown) may conduct steam at about 100 p. s. i. into chamber 16, thereby to heat the fixed head section when the operator turns the steam on by means of a pedal-controlled valve or the like (not shown). Another

2

pipe 17a also coupled to head 14 provides a return line for the condensate formed from the steam when the device is in use.

Complemental to the fixed head 14 is a swingable head 20 having a more or less flat and enlarged top 21 which lies in the general plane of the top surface 15 when the swingable head is upright as in the full line position of Fig. 1. The swingable head 20 is preferably of some solid material, that is, it has no provision for being heated internally by steam. As shown in Fig. 2 the swingable head subtends an angle of approximately 140°. Both the fixed head 14 and the swingable head 20 are provided with overhanging portions 14a, 20a respectively, the purpose of which is to fit into the flaring portion of a cap cover C, shown in phantom in Fig. 1. To permit the cap cover to be placed over the flared portions of the head sections, the swingable head is 20 swung to the left as shown in dotted lines, then the cover is positioned and the head is swung back until it contacts the interior of the cover. It will be understood that the grommet or stiffening wire of the cap has been removed prior to 25 washing the cap cover and that it is not replaced until after the ironing has been completed with the aid of the described device.

To mount the swingable head to swing as desired, the lower end of the swingable head is 30 shown as having a horizontal bore 22 receiving a rod 23 which also extends through a pair of aligned bearings or ears 24, integral with and upstanding from base 10, and a set screw 26 may secure the swingable head upon the rod, so that the rod acts as a rock shaft. One end of the rod 23 has a right angular extension or lever arm 27 which is designed to extend upwardly slightly out of the vertical, as shown, when the parts are in normal or operating position. At its 35 upper end lever arm 27 carries a removable metal ball 28 or other weight. Obviously the angularity of the lever arm may be varied at will by merely loosening the set screw, turning the rod or rock shaft 23 and retightening the screw. The lever arm facilitates manual swinging of the swingable head to permit placing a wet cap cover or removing a freshly ironed one. The angular position of the weighted lever arm also imposes a constant stress or stretch on the fabric of a cover held on the form, which is most desirable when ironing. It will be clear that this stress may be increased by lengthening the moment arm (which is accomplished by merely adjusting the angularity of the lever arm so that it is more nearly horizontal) or else by replacing the ball weight

28 with a heavier weight. It will also be seen that the action is automatic: each time a wet cap cover is placed on the form the latter will expand (because of movement of the swingable head away from the fixed head by the action of the weighted lever) until it engages the cap with equal force on opposite sides. Obviously the swingable head permits the device to be used with all sizes of cap covers. In Fig. 1 the dotted lines at the right indicate the positions of the head and lever arm when a large cap cover is in place on the form.

When using the device, after a cap cover has been positioned, slightly more than one-half of it is ironed by passing an iron or other pressing means over that part which is supported by the flat surface 15; then the cap cover, without removing it from the form, is turned through 180° and the remaining portion is pressed or ironed. The 210° arc of surface 15 permits pressing slightly over one-half of the cap cover at a time, which insures a complete pressing job with only one turn of the cover. The turning is of course effected after loosening the cover by swinging the lever arm inwardly.

Obviously a number of changes may be made in the described construction without departure from the spirit of the invention. For example the fixed head could be heated internally by electricity instead of by steam; also the swingable head could be otherwise mounted so as to be automatically movable away from the fixed head; or if desired the swingable head could be slidable toward and from the fixed head and moved by a spring instead of a weight. Other simple changes will be obvious to those skilled in the art.

What I claim is:

1. A pressing device for garrison cap covers and the like comprising a support; a hollow head fixed to the support and having a top adapted to form a smooth pressing surface; means including a source of steam for internally heating the fixed hollow head; a movable head shaped complementarily to the fixed head and forming therewith a support for a garrison cap cover; the movable head being pivotally mounted at its lower end on said support near the fixed head; operator-controlled means comprising a lever arm fixed to the movable head for moving the movable head into close proximity to and away from the fixed head; and a weight fixed to the outer end of the lever arm and constituting automatic continuously operating means acting on the movable head to effect separation of the heads except when the operator moves the movable head toward the fixed head.

2. The invention defined in claim 1 wherein the lever arm also extends through the lower part of the movable head to provide a rock shaft; the base having a pair of ears providing bearings for the rock shaft; the rock shaft being angularly adjustable relative to the movable head

so as to adjust the angularity of the lever arm and hence the length of the moment arm.

3. A pressing form for garrison cap covers and the like comprising a support; a head fixed to the support and extending above it and having a substantially flat smooth top surface subtending an angle of at least 210°; said fixed head being hollow and having means connecting its interior with a source of steam, so that a cap cover placed thereon may be heated to a pressing temperature; a movable head mounted on said support and having a top surface shaped complementarily to the top surface of the fixed head and adapted to lie in substantially the same plane; said top surfaces together supporting a garrison cap cover; the movable head being free of any connection with a heat source; operator-controlled means to move the movable head toward and away from the fixed head; and automatic continuously operating means to effect separation of the heads except when said operator-controlled means overpowers the means for moving the movable head.

4. A pressing device for garrison cap covers and the like comprising, in combination, a support; a hollow head fixed upon said support and having a top adapted to form a smooth pressing surface; a movable head having a top surface shaped complementarily to the top of the fixed head so as to form therewith a holder for garrison cap covers; the lower end of the movable head being pivotally mounted on said support near the lower end of the fixed head so as to swing about a horizontal axis away from the fixed head and in close proximity thereto; operator-controlled means comprising a lever arm fixed to the lower end of the movable head and adapted to swing the movable head; a weight fixed to the outer end of the lever arm; the lever arm being at such an angle relative to the vertical as to provide a moment arm for the weight, said weight and lever together constituting automatic continuously operating means acting on the movable head to effect separation of the heads except when the operator swings the lever in a direction opposite to that in which the lever is swung by said weight; and means for heating the fixed hollow head including the top thereof.

PAUL A. LOOMIS.
